GOLF-CLUB HOLDER

Application filed February 27, 1929, Serial No. 342,980, and in Great Britain November 6, 1928.

Our invention relates to improvements in bags or holders for golf clubs in which the golf clubs are carried in separate compartments to prevent the clubs from slipping about in the bag or rattling together and facilitate the selection of any particular club when required for use.

The object of our invention is to provide an improved bag of the above type.

- 10 According to this invention a bag or holder for golf clubs is divided into a series of separate compartments by means of a cellular or partitioned member preferably formed of fabric or other suitable flexible material.
- 15 This cellular member or partition is constructed in a form to provide a number of separate compartments rectangular in shape formed in a rectangular body which is suspended at two diagonally opposite corners 20 in the upper open end of the bag so that it will hang down inside the bag to any desired depth but is preferably of a sufficient length to extend right to the bottom of the bag so as to keep each club entirely separate 25 from its neighbour.

In carrying our invention into practice we prefer to employ a cellular compartment member comprising a series of pieces of fabric sewn together at suitable intervals so that 30 when the said member is opened out due to its diagonal suspension a series of substantially rectangular chambers will be formed between the pieces of fabric. In a suitable arrangement for forming a series of nine separate 35 compartments a single piece of fabric may be folded upon itself and the two faces stitched together at their edges and along two intermediate lines. To the opposite outer faces of the two halves of this piece of fabric are secured two further pieces sewn along lines 40 which lies intermediate between the edges and the points of attachment of the first piece of fabric. A somewhat narrower strip is again secured on the outer face of each 45 of these two second strips, their edges being sewn at two points intermediate between the points of attachment between the second strip and the first strip. When the two latter strips are pulled apart in opposite directions the various pieces of fabric will be stretched out to

form pockets or cells of substantially rectangular shape stretched apart in a direction extending diagonally across their corners. The upper edges of the fabric forming these cellular partitions may be reinforced by 55 binding with leather or other suitable strengthening strips which are folded over the upper edges and sewn in position.

The cellular partition with its series of separate compartments may be secured in the 60 upper open end of the bag by attaching its four opposite corners to the rim of the bag preferably by leather or other strips sewn to the corner cells and secured to the rim of the bag.

We now propose to describe our invention with reference to the accompanying drawings wherein:

Fig. 1 is a side elevation of a golf club holder with transverse section showing the 70 partitioned member located therein.

Fig. 2 is a part vertical section.

Fig. 3 is a plan view, and

Fig. 4 is a detail to be referred to.

The outer container 5 is of about usual 75 construction and is provided with any desired attachments such as studs 6, handles 7, strap 8 and support 9 for an umbrella, and strap 10 whereby the container may be drawn in to encircle and secure the clubs at its upper 80 end and to prevent entrance of rain.

Secured to the upper edge or rim of the container by a leather or other strip 12 is a metal or other strengthening or stiffening rod 13.

The partitioned member may comprise (see transverse section in Fig. 1) a single piece of fabric 14 folded in half and stitched together at its edges by a line of stitches 15 and by two intermediate lines of stitches 16. 90 To the outer faces of the two halves of this piece of fabric 14 are secured two pieces 17, 18, sewn along lines 19, 20, 21, and 22, 23, 24 respectively, each of which lines lie intermediate between the lines 15 and/or 16. A narrower strip 25 is sewn to the strip 18 by a line of stitches 26 that is intermediate between the lines 22, 23, and by a line of stitches 27 that is intermediate between the lines 23, 24. A strip 28 is secured to the strip 17 in 100

a similar manner. When the strips 25 and 28 are pulled apart in opposite directions the various pieces of fabric will be stretched out to form pockets or cells of substantially 5 rectangular shape stretched apart in a direction extending diagonally across their corners.

The upper edges of the fabric forming the 10 partitioned member is reinforced by binding with a leather strip 31, and may be attached to the holder 5 by leather strips 32 that pass round the rod 13. These attaching strips may be secured round the rim or rod 13 and under the binding material 12 as shown in Figs. 2 15 and 3. If desired the partitioned member may be provided with leather loops 35 that pass through slots 36 in spring hooks 37 adapted to engage over the rim of the holder to secure said member detachably to the holder so that said member may be fitted to a bag or holder already made up or in use.

In addition to the series of chambers formed within the partitioned or cellular member, four other compartments 29 will 25 also be provided between the member and the bag or holder at positions intermediate between the various attaching strips which secure the partition in the bag. The cellular partition may extend down into the bag to 30 any desired distance but is preferably long enough to extend right to the bottom of the bag thus ensuring a complete separation of the golf clubs. The cellular partition may be constructed of the same materials as the 35 bag and is preferably of a waterproof character, but soft leather or any other suitable material may be employed if desired.

We claim:-

1. A golf club holder comprising an outer 40 container and a partitioned flexible member of substantially rectangular cross section when opened out located within said container and comprising a piece of flexible material folded upon itself and united at intervals along lines parallel to the fold, and a piece of flexible material united to the folded piece along lines parallel to the fold and intermediate the first mentioned lines, and an equivalent number of pieces of flexible 45 material united directly or indirectly to the folded piece on each side thereof, each piece being united to the adjacent piece along lines parallel to the fold and intermediate the adjacent series of lines of attachment, the 50 said partitioned flexible member being suspended by diagonally opposite corners whereby it is opened out to disclose a plurality of 55 rectangular pockets.

2. A golf club holder comprising an outer 55 container, a partitioned member located within said container, flexible loops on said member, and a spring clip for each loop having a slot through which said loop passes, said member being detachably secured by 60 said clip to said holder.

3. A golf club holder comprising an outer 70 container, a partitioned flexible member of substantially rectangular cross section suspended within said container, flexible loops on diagonally opposite corners of said flexible partitioned member, spring clips one for each loop having slots through which said loops pass, said flexible member being detachably suspended by said clips in said outer container so that it is opened out to disclose a plurality of rectangular pockets 75

4. A golf club holder comprising an outer 80 container, a partitioned flexible member of substantially rectangular cross section suspended within said container and comprising a piece of flexible material folded upon itself and united at intervals along lines parallel to the fold, and a piece of flexible material united to the folded piece along lines parallel to the fold and intermediate the first mentioned lines and an equivalent number of pieces of flexible material united directly or indirectly to the folded piece on each side thereof, each piece being united to the adjacent piece along lines parallel to the fold and intermediate the adjacent series of lines of attachment, flexible loops at the top, middle and points of several of the ends of said first mentioned folded piece of material, loops at the middle of the external folded 90 pieces of material secured directly or indirectly to the said first mentioned piece of folded material, spring clips one for each loop having slots through which said loops pass, said flexible member being detachably 95 suspended by said clips in said outer container so that it is opened out to disclose a plurality of rectangular pockets. 100
